Meyers, Caravagh & Hyde

UNITED STATES PATENT OFFICE.

JONATHAN PETERSON, OF BROOKLYN, NEW YORK, ASSIGNOR TO COMBINATION MACHINE COMPANY, OF NEW YORK, N. Y., A CORPORATION OF DELAWARE.

CARTON.

1,425,835.

Specification of Letters Patent. Patented Aug. 8, 1922.

Application filed January 28, 1921. Serial No. 440,587.

To all whom it may concern:

Be it known that I, JONATHAN PETERSON, a citizen of the United States, and resident of Brooklyn, county of Kings, and State of New York, have invented certain new and useful Improvements in Cartons, of which the following is a specification.

My invention relates to a new package or carton, important characteristics of which are low cost, both in material and methods of production, lightness and convenience, both as a packing and shipping container, and as a retailing or display container.

The carton has been developed with especial reference to use for packaging such articles as small boxes or packages of cigarettes, and the advantages of the invention will be sufficiently understood by reference to such a use, although it is not limited to such use and is available for packaging articles and commodities of great variety.

Boxes or cartons heretofore used for enclosing a group of cigarette packages and other commodities have usually been made largely of card-board or other relatively heavy and stiff material in order to permit of rapid production of containers on a large scale, and to facilitate filling and closing the cartons either by hand or machine operations on a large production basis. Boxes heretofore used for such purposes have also usually been of such a nature that in order to make the package dirt and moisture proof the packed carton has to be enclosed in another wrapping, such as glacie or other paper, with evident additional expense.

An important object of my invention is to provide a container or carton which may be made of relatively thin and inexpensive paper; which is also adapted for rapid and mechanical production on a large scale, either by hand or machine operations; which is readily filled with goods of the desired class and readily closed by hand or machine operations on a large out-put basis; and which when completed by closing, provides in itself a substantially dirt- and moisture-proof covering for the contained goods, without the necessity for further wrapping.

To attain these objects the carton comprises, in one embodiment, a main or body portion, usually of prismatic form with one open side, of relatively thin paper, which may be of varying grades, but for the sake of economy may be of relatively cheap quality, constructed and arranged so that

marginal portions may be turned outward and after the body is filled a cover or top sheet may be placed upon the open side of the body and adhesively secured to the body 60 margins and the marginal portions of both the body and cover then turned down and adhesively secured to sides of the body. Desirably, in most cases, a filler piece of paper or card-board is placed upon the contents of 65 the package and beneath the cover piece before or as the latter is applied, and this filler may in some cases be adhesively secured to the cover piece.

The characteristics and advantages of the 70 invention are further sufficiently explained in connection with a detailed description of the accompanying drawings which show one exemplifying embodiment of the invention. After considering this it will be understood 75 that many variations may be made within the principles of the invention and I contemplate the employment of any structures which are within the scope of the appended 80 claims.

In the accompanying drawing:

Fig. 1 is a perspective view of a suitable blank for the main or body portion of the carton.

Fig. 2 shows the blank folded into partial 85 box form.

Fig. 3 shows the body completed, with marginal portions turned down, and filled, and a filler piece in position over the contents, a part of the filler piece being torn 90 away.

Fig. 4 shows the top or cover piece in position.

Fig. 5 shows the complete covered carton.

Fig. 6 is an enlarged fragmentary detail 95 showing the structure and method of opening the carton.

Fig. 7 shows a gummed cover piece.

Fig. 8 shows a filler piece in assembled relation to a cover piece.

Fig. 9 is a transverse section of the completed carton.

The main or body portion B of the container is desirably formed from a single piece of paper or relatively thin card-board 105 which may be shaped as shown in Fig. 1, although the blank form and details of construction of the carton body may be varied greatly. In this case the body blank B comprises a main or bottom portion 1, side wings 2 having margins 3, end wings 4 having margins 5 and end or corner laps 110

6, which in this case extended from the ends of the side wings. Desirably the blank is scored or creased along the lines 7 to facilitate a subsequent folding and is cut 5 along the lines 8 to separate the corner laps from the end wings. Adhesive 9 is applied to the upper surfaces of the corner laps.

This blank is folded up as shown in Fig. 2 with the side and end wings vertically 10 arranged and adjacent to each other, and the corner laps 6 are then folded in and adhesively secured to outer surfaces of the end wings. Margins 3 and 5 of the side and end wings extend up in line with their respective wings. At a suitable step in the 15 formation of the carton adhesive stripes 10 are applied to outer surfaces of these margins 3 and 5. This adhesive application may be made at the stage represented in 20 Fig. 2, or later as may be desired.

The body may be filled with suitable contents, such as a plurality of boxes A of cigarettes, as shown in Fig. 3, at any time after the box formation of the body blank 25 has been sufficiently completed. When the commodity for which the carton is intended has a standard size, such as a cigarette box or package, the carton body is, of course, designed so that it will receive a suitable 30 number of the commodity packages in compact layer and row arrangement. The bodies may be filled before or after margins 3 and 5 are turned outward to substantially horizontal position, as shown in Fig. 3. 35 The filled body is now ready for completion by covering. Desirably a filler piece F, of a size to closely fit the interior of the carton body is laid upon the contained articles, as shown in Fig. 3, substantially one-half 40 of the filler piece being there broken away to disclose the contents of the package. This filler piece protects the package contents and also assists in reinforcing and stiffening the cover piece, and also aids in 45 opening the package, as hereafter explained. In some cases the filler piece is desirably associated with the cover piece C, Fig. 8, and the two pieces are then put in position upon the filled carton body.

50 The cover piece C is usually of relatively thin paper and it may in fact be of somewhat thinner stock than the body material, especially when it is reinforced by a filler piece. The thickness and grade of the 55 cover paper may be chosen with due regard to structural requirements, economy or the desired package finish. One surface of the cover piece is coated with adhesive 12 and the cover is then laid upon the carton body in contact with the filler piece and extended margins 3 and 5, or the filler piece is first associated with the adhesively coated cover as shown in Fig. 8, and the 60 two are then applied to the package, the 65 filler piece serving the purposes above in-

dicated and also protecting the package contents from adhesive and also serving to locate the margins of the cover properly in relation to body margins 3 and 5. In either case the cover is properly pressed in 70 position with its margins in contact with body margins 3 and 5 so that these portions adhere together throughout the area of body margins 3 and 5, corner portions 75 of the cover being free from any portions of the body material. The package is then in the condition shown in Fig. 4, in which an upper side portion of the body and cover material are torn away to show the package 80 contents and a portion of the filler piece. 80

The horizontally extending margins 14 and 15, each comprising marginal portions of the cover and of the body material are now folded down and secured against the sides and ends of the body structure as 85 shown in Fig. 5, these margins being retained by adhesive stripes 10 previously applied to the under sides of body margins 3 and 5 at any suitable stage in the production process, as previously explained. 90 The cover corners 13 are disposed of either by inturning them under adjacent portions of margins 14 or 15, or by folding them over upon outer surfaces of these marginal portions as shown at 16, Fig. 5. 95

The complete container or package thus produced is substantially dirt-proof and may be substantially moisture-proofed to the extent desired, by providing materials which are properly waxed or oiled. No 100 additional outer wrapping is needed for the packages. While made of relatively thin and flexible material the packages have substantial rigidity ample for the desired purpose by reason of co-operation of the package contents with the closely fitting carton members. 105

The package may be readily opened by running a finger nail along the upper surface of the package very close to the sides 110 and ends whereupon the cover paper C will be easily severed between the upper edges of the body side wall material and the adjacent edges of the filler piece F. The partial severing of the cover for the purpose of 115 opening the package is indicated in Fig. 6, in which a corner of the cover and connected filler piece are raised, showing a portion of the package contents.

The package having the described characteristics is especially valuable for retail vending because the cover may be partially or entirely severed to remove part or all of the contents of the carton and as long as any of the contents remains the carton may be used as a container, instead of being practically destroyed in the act of opening the package to get at any of the contents, as usually happens with containers heretofore provided for articles of this class. 130

What I claim is:

1. A container of relatively thin and flexible fibrous sheet material, comprising a body and a cover, marginal portions of the cover being secured to marginal portions of the body and the combined marginal portions being adhesively secured against adjacent wall portions of the body. 5
2. A container of relatively thin and flexible fibrous sheet material, comprising a main portion or body having an open side and having marginal portions at the open side, a filler piece located in the open side of the body, and a cover piece overlying the 10 filler piece and having margins secured to the marginal portions of the body, the combined marginal portions of the body and cover being adhesively secured to side portions of the body. 15
3. A container of relatively thin and flexible fibrous sheet material, comprising a main portion or body having an open side and having marginal portions at the open side, a filler piece located in the open side 20 of the body, and a cover piece adhesively secured to the filler piece and having margins secured to the marginal portions of the body, the combined marginal portions of the body and cover being adhesively secured to 25 outer surfaces of the body walls. 30
4. A container comprising a paper body having an open side and margins at the open side, a filler piece substantially co-extensive with the open side of the body, a paper cover piece adhesively secured to the 35 filler piece and having margins adhesively secured to the body margins, the combined body and cover margins being turned down against outer wall surfaces of the body and 40 adhesively secured thereto. 45
5. A paper carton comprising a body blank having a bottom portion, side and end wings, corner laps and side and end margins, a filler piece, and a cover piece adhesively secured to the filler piece and having margins adhesively secured to the body margins, the combined body and cover margins being turned down and adhesively secured to ends and sides of the body. 50
6. A package enclosure of relatively thin, flexible material reinforced by co-operation with the package contents, said enclosure comprising a body substantially enclosing all sides but one of the contents mass, a cover piece enclosing the other side of the contents mass, the body and cover having composite marginal portions turned down and adhesively secured to sides and ends of the body. 55
7. A package enclosure of relatively thin, flexible material reinforced by co-operation with the package contents, said enclosure comprising a body substantially enclosing all sides but one of the contents mass, a cover piece enclosing the other side of the 60
- contents mass, the body and cover having composite marginal portions turned down and adhesively secured to sides and ends of the body and a filler piece lying on the contents mass beneath the cover. 70
8. A container comprising a body of paper and a cover of thinner paper, marginal portions of the cover being secured to marginal portions of the body and the combined marginal portions being adhesively 75 secured against adjacent wall portions of the body. 80
9. A container comprising a main portion or body of moderately thick paper having an open side and having marginal portions at the open side, a filler piece of thicker material located in the open side of the body, and a cover piece of paper thinner than the body material overlying the filler piece and having margins secured to the marginal portions of the body, the combined marginal portions of the body and cover being adhesively secured to side portions of the body. 85
10. A container comprising a main portion or body of moderately thick paper having an open side and having marginal portions at the open side, a filler piece located in the open side of the body, and a cover piece of relatively thin paper adhesively secured to the filler piece and having margins secured to the marginal portions of the body, the combined marginal portions of the body and cover being adhesively secured to side portions of the body. 90
11. A container comprising a thin and flexible paper body having an open side and margins at the open side, a filler piece substantially co-extensive with the open side of the body, and a cover piece of relatively thin paper adhesively secured to the filler piece and having margins secured to the margins of the body, the combined body and cover margins being turned down against side and end portions 100 of the body and adhesively secured thereto. 105
12. A carton comprising a body of moderately thick paper in substantially box form with one open side and having margins at sides and ends of the open side, a filler piece of relatively heavy paper inserted in the open side of the body, and a cover piece of relatively thin paper adhesively secured to the filler piece and having margins adhesively secured to the body margins, the 110 combined cover and body margins being turned down and adhesively secured to sides and ends of the body structure. 120
13. A carton comprising a body blank of paper material of moderate thickness and having a bottom portion, side and end wings, corner laps and side and end margins, a filler piece of relatively thick material and a cover piece of relatively thin material adhesively secured to the filler piece and hav- 125 130

ing margins adhesively secured to the body margins, the combined body and cover margins being turned down and adhesively secured to ends and sides of the body.

- 5 14. A package enclosure of relatively thin material reinforced by co-operation with the package contents, said enclosure comprising a body substantially enclosing all sides but one of the contents mass, a relatively thin 20 cover piece enclosing the other side of the contents mass, the body and cover having composite marginal portions turned down and adhesively secured to sides and ends of the body, and a relatively thick filler piece 25 lying on the contents mass beneath the cover.
- 10 15. A package enclosure of relatively thin

material reinforced by co-operation with the package contents, said enclosure comprising a body substantially enclosing all sides but one of the contents mass, a relatively thin 20 cover piece enclosing the other side of the contents mass, the body and cover having composite marginal portions turned down and adhesively secured to sides and ends of the body, and a relatively thick filler piece 25 lying on the contents mass beneath the cover.

Signed at New York, in the county of New York and State of New York, this 25th day of January, A. D. 1921.

JONATHAN PETERSON.
